UNITED STATES PATENT OFFICE.

LÉON E. LYON, OF NORFOLK, VIRGINIA.

CONCRETE PILE.

1,128,773.

Specification of Letters Patent.

Patented Jan. 5, 1915.

Application filed January 14, 1913. Serial No. 741,956.

To all whom it may concern:

Be it known that I, LÉON E. LYON, a citizen of the United States, residing at Norfolk, Norfolk county, in the State of Virginia, have invented certain new and useful improvements in Concrete Piles, of which the following is a full, clear, and exact specification.

My invention relates to improvements in concrete piles, and the same has for its object, more particularly to provide a novel form of pile having an enlarged subterranean base or foundation which may be formed either before or after the pile has been set or driven into the position it is intended to occupy.

Further said invention has for its object to provide means for forming an enlarged subterranean cavity by means of a suitable explosive agent which is so disposed as to avoid the cushioning action of the air, and thus render the explosive agent more effective in enlarging the area of the cavity.

Further said invention has for its object to provide a concrete pile possessing the requisite degree of hardness and strength for the object in view, and which is provided at its lower end with a point of relatively weaker concrete or other suitable material having a cavity to receive the explosive charge.

To the attainment of the aforesaid objects and ends my invention consists in the novel details of construction and in the combination, connection and arrangement of parts hereinafter more fully described, and then pointed out in the claims.

In the accompanying drawings forming part of this specification wherein like numerals of reference indicate like parts—Figure 1 is a central vertical section showing a previously formed concrete pile having a point of relatively weaker concrete formed at the lower end thereof provided with a cavity to receive an explosive charge, and the body of the pile provided with a central longitudinal opening communicating with the cavity in said point and adapted to receive a fuse; Fig. 2, is a similar view showing the explosive agent discharged, the point of said pile shattered or destroyed, and an enlarged cavity formed at the base of the pile; Fig. 3, is a similar view showing a concrete base or foundation formed at the lower end of the body of the pile, and the opening in said pile filled with concrete

in order to form a homogeneous structure, and Fig. 4 is a detail side elevation showing the lower portion of a pile.

In carrying out my said invention I employ a previously formed concrete pile 20 having a central longitudinal opening 21 therein extending entirely through the body portion of said pile, and form at the lower end of said pile a point 22 of relatively weaker concrete than that of which the body portion of said pile is composed. I also provide the point 22 with a central recess or chamber 23 which registers with the opening 21 in the body portion of the pile, and within said recess or chamber I place an explosive agent 24, such as dynamite or other suitable agent. By preference the lower end of the body portion of the pile is made straight in order that the pile shall rest properly upon its base or foundation, and the point 22 is preferably made of tapering form as illustrated to facilitate the driving of the pile. After the pile has been driven to the desired extent, the explosive agent 24 is discharged, whereby the point 22 will be shattered and caused to cleave from the lower end of the pile 20. By the action of the explosive agent an enlarged cavity 25 will be formed at the base of the pile 20 as shown at Fig. 2. Hereupon the cavity 25 may be filled with concrete 26 through the central opening 21 in the pile, to form a base 27, and finally said opening 21 filled with concrete thus forming a solid homogeneous pile and base therefor.

It will of course be obvious that the body of the pile may be of plain concrete or other suitable plastic material or of such material reinforced by suitable means, as desired. Further it is to be noted that by inclosing the explosive charge in a relatively weak concrete block or point, I avoid the cushioning effect of the air, which occurs where the explosive is not so inclosed, and thus render the explosive medium more effective, and produce a larger cavity.

Heretofore when a cavity was to be enlarged by explosives, the method has been to fire successive charges of explosive, beginning with small charges and gradually increasing the amount, thus consuming much explosive and time, for the hole must be allowed to cool after each explosion before placing the next charge under this method. The cushioning effect of the air diminished the effect of the explosion on the

earth, and only a small enlargement took place at each shot unless very large charges were used. This would not only be expensive but would tend to loosen the ground above the base of the pile. In order to enlarge a hole from one foot to three feet in diameter as many as ten shots might be necessary. By placing the explosive in a solid block the explosive acts directly upon the surrounding earth and there is no cushioning effect. The earth is pushed aside or compacted and the cavity formed. One shot properly placed in this way will give the desired result, and the shattered concrete blocks will form suitable aggregates to combine with the concrete which is subsequently deposited.

Having thus described my invention what I claim as new, and desire to secure by Letters Patent is:

- 20 1. A pile comprising a body portion formed of concrete, and a point adapted to receive an explosive medium, formed integrally with said body portion of relatively weaker material than said body portion, substantially as specified.
- 25 2. A pile comprising a body portion formed of plastic material, and a point, provided with means to receive an explosive charge, formed integrally with said body portion of relatively weaker plastic material than said body portion, and having a definite plane of cleavage between said body portion and said point, substantially as specified.
- 30 3. A pile comprising a body portion formed of concrete, a point formed integrally thereon of relatively weaker concrete, and means arranged in said point for receiv-

ing an explosive medium, substantially as specified.

4. A pile comprising a body portion 40 formed of concrete having a central opening extending therethrough, and a point of relatively weaker concrete formed integrally with said body portion at one end thereof; said point having a chamber there- 45 in communicating with the opening in said body portion and adapted to receive an explosive medium, substantially as specified.

5. A pile comprising a body portion formed of concrete having a central opening 50 extending therethrough, a conical point of relatively weaker concrete formed integrally with said body portion at one end thereof; said conical point having a recess therein communicating with and forming a continu- 55 ation of the passage in said body portion, substantially as specified.

6. A pile comprising a body portion formed of plastic material, and a point, provided with means to receive an explosive 60 charge, formed integrally with said body portion of relatively weaker plastic material than said body portion, and having a definite plane of cleavage between said body portion and said point, substantially as 65 specified.

Signed at the city of Norfolk, in the county of Norfolk, and State of Virginia, this 30th day of December, 1912.
